(57) CLAIM

The ornamental design for a hose reel enclosure, as shown and described.

DESCRIPTION

FIG. 1 is a top right isometric view of the hose reel enclosure of the present invention;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a top right isometric view thereof; and,

FIG. 8 is a back right view thereof.

The portions of the hose reel enclosure illustrated in broken lines form no part of the claimed subject matter.
